UNITED STATES PATENT OFFICE.

FRED R. TAISEY, OF LOWELL, MASSACHUSETTS, ASSIGNOR TO THE LAMSON COMPANY, OF BOSTON, MASSACHUSETTS, A CORPORATION OF NEW JERSEY.

PNEUMATIC-DESPATCH-TUBE CARRIER.

1,393,466.

Specification of Letters Patent. Patented Oct. 11, 1921.

Application filed June 12, 1917. Serial No. 174,369.

To all whom it may concern:

Be it known that I, FRED R. TAISEY, a citizen of the United States, residing at Lowell, in the county of Middlesex and State 5 of Massachusetts, have invented certain new and useful Improvements in Pneumatic-Despatch-Tube Carriers, of which the following is a specification.

This invention relates to an improved carrier for pneumatic despatch tube systems and has for one of its objects the provision in combination with such a carrier of means for unloading or for facilitating the unloading of said carrier.

Another object of the invention is to provide an improved closure for carriers, which on account of its positive action, neatness of construction, and the elimination of the usual latch, especially commends itself to 15 meet the exacting requirements of carrier service.

Still another object of the invention is to so combine the article ejecting means with the closure of the carrier as to reduce the 20 number of movable parts substantially to a minimum and to correspondingly simplify the construction of the carrier as a whole.

These and other objects of my invention will be hereinafter referred to and the novel 25 combination of means and elements whereby said objects may be obtained, will be more particularly pointed out in the claims appended hereto.

In the accompanying drawing which 30 forms a part hereof and in which like reference characters designate like parts in the respective views, I have exemplified a preferred embodiment of my invention; but as I am aware of various changes and modifications 35 which may be made herein without departing from the spirit of the invention, I desire to be limited only by the scope of said claims.

Referring to the drawing:

Figure 1 is a side elevation of the improved carrier, partly broken away to show the details of construction thereof.

Fig. 2 is a fragmentary detail section, taken on the line II—II of Fig. 1.

Fig. 3 is a bottom view of the carrier, showing the cover in its closed position.

Fig. 4 is a similar view with the cover in its open position.

Fig. 5 is a detail section taken on line 55 V—V of Fig. 2.

Fig. 6 is a similar section taken on line VI—VI of said figure; and

Fig. 7 is a side elevation, broken away in correspondence with the lower end of the sectioned part of Fig. 1, but showing a modification of the latch hereinafter described.

The carrier preferably consists of a tubular body 1, made of leather, fiber, or the like; a brass cup or cap 2 being riveted fast upon one end of said body.

This cup is shown in its inverted position in Fig. 1, and has secured to the bottom or outer flat surface thereof the usual felt head 3, or the like, this head being conveniently held in position by means of bolts 4, the heads of which are countersunk into a disk or plate 5, which is received into a recess 6 in the face of the head 3.

A plate or strip 7 acts as a nut which is common to both of the bolts; the latter being 75 screwed thereinto, and preferably having their ends peened over, as shown, to prevent inadvertent separation of the head from the carrier proper.

At the lower end of the carrier shown in 80 Fig. 1, is a skirt 8 of flexible leather, to aid in maintaining pressure back of the carrier during its propulsion through the tube in which it travels.

A strip or plate 9, of sheet metal or the like, is riveted longitudinally to one side of the interior wall of the carrier; this strip preferably being bent, as at 9', to better conform it to the curved surface of the carrier, while at the same time preserving a flat surface longitudinally down the middle of the strip, to provide a bearing for the flat strip or rod 10, hereinafter referred to.

Near its inner end, the strip or plate 9 is 85 slit laterally and inwardly from the respective edges thereof, to permit the tongues 11 to be turned in, as best shown in Figs. 2 and 5, to substantially embrace or inclose the strip 10; while corresponding slits are formed in the plate 9 relatively near the 90 outer end thereof, to permit the formation of corresponding, but preferably shorter tongues 11'.

The slidable connection or strip 10 carries on its inner end means for engaging the 105 inner extremity of the papers or other article which may be emplaced in the carrier, to the end that when said connection is partly withdrawn, said papers will be correspondingly forced out or ejected from the carrier.

The means in question is most conveniently formed by simply bending over the inner end of the strip 10, at substantially right angles, as shown at 10'.

5 In order to maintain the construction as simple as possible, the outer end of said strip 10 is notched inwardly or cut away, as at 12, so that prongs of the bifurcated end, thus formed, may be turned or rolled 10 over, as at 13, to provide bearings for the pintle 14 which unites the strip 10 to the cover shank 15; the inner end of this shank being correspondingly cut away as at 16 and the so formed laterally disposed prongs being overturned as at 17 to provide bearings 15 for the extremities of the pin or pintle 14.

As best shown in Figs. 2 and 4, therefore, the bearings 13 are disposed between the bearings 17, and the shank 15 is pivotally 20 connected to the strip 10 by the pintle 14.

On the pin 14 and between the bearings 13 is disposed a light coil spring 18, the respective extremities 18' of which bear against the strip 10 and shank 15, so as to tend to 25 swing said shank around at right angles to the strip 10 as indicated in dotted lines in Fig. 1; these lines representing the positions of the engaging device and cover when the latter has been unlatched and the former 30 partly withdrawn from the carrier.

The shank 15 is preferably integrally united to the closure 19, and as shown in Figs. 1 and 3, said cover is preferably substantially circular, in correspondence with 35 the cylindrical tube, and is provided with a recess 19', into which the finger may be inserted when the carrier is to be uncovered and its contents removed. It is obvious however that the closure may be of any suitable shape to provide a stop to prevent inadvertent egress of the load in the carrier 40 during transit.

The plate or strip 9 is slotted through its outer end as at 20, to receive a tongue 21 45 which is struck out from the shank 15; said tongue being preferably formed by slitting the shank as at 21' and driving the so formed tongue out at an angle to the body of the shank.

50 To open, the operator's finger is pressed against the point designated A, in Fig. 3, to withdraw the tongue 21 from the slot 20 in which it is seated and permit the cover being drawn outwardly, at first substantially axially of the carrier. After the pintle 14 has cleared the edge of the carrier body, the cover is then free to swing around 55 into parallelism with the strip 10, as shown in Fig. 1.

60 As above stated, the spring 18, tends to impart this swinging movement to the cover and to so position it.

As the cover is thus drawn bodily away from the receptacle, the load ejecting end of the strip 10 pushes the roll of papers or other

articles which may be in the carrier, outwardly, so that said papers may be conveniently grasped by the fingers, or may be ejected completely out of the carrier, if the strip is pulled out suddenly.

70 The connection 10 is preferably closely guided by the plate 9 and its tongues 11 and 11', so that the normal movement of said connection is always in parallelism with the axis of the carrier; preferably, the said connection 75 is formed of spring metal, which tends to prevent its being inadvertently bent permanently out of shape; since the strip can be bent still farther to the left than is shown in dotted lines in Fig. 1, when said handle is 80 in its outermost position, by reason of the resiliency of strip 10, the entry of papers into the receptacle or removal of papers therefrom is facilitated.

85 On account of the action of the spring 18, when the carrier is unloaded and placed, for example, head down—as when standing upon a desk,—the shank 15 can in such case drop down into engagement with the edge of the skirt 8, so that the cover occupies substantially the position that it would if it were 90 hinged in ordinary fashion to the receptacle, and disposed in an open position, substantially parallel to the axis of the carrier; except for the added advantage that in the 95 present construction the plane of said cover is somewhat farther removed from said axis than would be the case if the cover had been directly hinged to the edge of the receptacle. As a result, papers or the like may be most 100 readily introduced into the carrier, and thereafter when the fingers are placed upon the cover and it is rocked around through 90° and thrust inwardly, it engages any of the papers which may have projected 105 slightly above the edge of the receptacle and drives them down into said receptacle.

Since also, the spring 18 normally tends to 110 rotate the cover or closure with respect to the connecting strip 10, in the manner above described, as soon as the cover has been pushed completely into its closed position and released, said spring rotates the shank 15 clockwise, as viewed in Fig. 1, to introduce the tongue 21 again into the slot 20, and thereby latch the cover. The inward movement of the cover in the manner described is 115 limited by the engagement of the bent end 10 with either the plate 7 or inner ends of the bolts 4.

120 While the rotatably mounted cover such as that described is convenient, the joint between the shank 15 and strip 10 may be avoided for economy and durability if desired by forming these parts integrally as shown in Fig. 7, the resilient strip 10" having an impressed backward bend to withdraw the integral bent cover 19" out of line with the body of the carrier when open.

125 In this case as there is no need for pro- 130

viding clearance for the end 18' of any coil spring, the lugs struck up from the plate 9, near the outer end of the latter, need not be cut short like those designated 11', but may 5 be full length, as at 11.

Herein, however, as in the previously described construction, the lugs 11 which replace the lugs 11', should preferably be disposed sufficiently inwardly from the mouth 10 of the receptacle to make provision for the requisite disengagement of a locking tongue 21' formed on strip 10 from its slot 20, to enable the withdrawal of the connection 10' and its attached parts. The resilient action 15 of said stem tends to keep said tongue 21' in its slot, when the cover 19'' is in its closed position; while this same resilient action also tends when the closure is in its outermost position, to swing said closure more or less 20 away from the axis of the receptacle, to favor the introduction of articles into the latter or their removal therefrom; the general course of the exposed part of this resilient strip 10'' being indicated in dotted lines 25 in Fig. 7.

Whether the cover be made separate from its slidable connection or integral therewith, is substantially immaterial, however, in so far as the general mode of operation of the 30 device is concerned; but the provision of a hinged cover, such as that shown in Fig. 1, except for the slight additional expense, is to be preferred; since, as above stated, it permits of the emplacement of the entire length 35 of the stem 10 within the receptacle when the cover is open and the device is standing or lying around on the desk. This position of said stem obviously prevents injury thereto.

40 It is also obvious that the cover forms a handle whereby the article engaging means can be operated; and while this handle has been shown in the form of a cover or closure, I do not desire to be necessarily limited 45 thereto.

In general, both of the above described 50 embodiments of my invention, afford a practical carrier in which articles such as papers or the like, may be safely despatched; neither the carrier nor its contents being subject to injury, as by a rear end collision 55 between closely following carriers in course of transit; while it will be particularly observed that there is no latch on the cover which is separately movable with respect to the latter, and hence more or less subject to injury; and, moreover, there is preferably 60 no latching device of any description on the side of the carrier away from or opposite the side at which the cover is hinged or otherwise attached.

The cover may be opened or closed with practically but a single movement of the hand of the operator; and if the ejector be 65 provided in combination therewith, as shown,

the carrier can be unlocked, its cover opened and its contents either positively discharged or placed in a most accessible position for removal from the carrier, all by said single movement. The importance of 70 this simplicity of operation, as a time and labor saver, in an art wherein readiness and speed of operation is of substantially the first importance, is, of course, at once apparent. 75

Having thus described my invention what I claim is:

1. A tubular carrier for pneumatic despatch tubes, having an opening in one end thereof to receive articles to be carried, a 80 closure device to prevent the inadvertent egress of said articles from said carrier, means to mount said device for movement laterally with respect to the axis of said carrier and also for opening movement substantially longitudinally of said axis, said device having provisions to permit of lateral displacement thereof when in its closed position, and means to normally retain said closure device in its closed position and 85 against longitudinal movement, after being closed, said retaining means comprising engageable locking parts which are inoperatively disposed with respect to each other when said device, as aforesaid, is laterally 90 displaced as aforesaid, to permit of said longitudinal opening movement. 95

2. In a carrier, the combination of a receptacle with a closure device therefor, means to mount said device for movement 100 bodily outward from the mouth of said receptacle and also for movement substantially in the plane of said device, said means having provisions normally tending, when said device is in its closed position, to resist 105 movement thereof in a direction away from a determined side of said receptacle, and means, to co-act with said provisions, to hold said device against said bodily outward movement thereof when in its said closed 110 position, said last mentioned means being rendered inoperative to resist said outward movement when said device is moved in the said direction away from said determined side of the receptacle. 115

3. In a carrier, the combination of a receptacle with a closure device therefor, guides attached to one side of said receptacle, supporting means for said device having a portion thereof in sliding engagement with 120 said guides, latching parts, one of which is carried by said supporting means, for holding said supporting means against opening movement of said device, and provisions to permit said latching parts to be separated 125 by a movement of said closure device substantially in its own plane, to permit of said device being moved to its open position.

4. A pneumatic despatch tube carrier having therein a slidable connection mounted 130

at one side of the interior of said carrier and extending longitudinally of the latter, load ejecting means to engage the load to be despatched in said carrier, and operable by said slidable connection, a closure for said carrier at the outer end of said connection and operable together therewith, said closure being movable out of line with the interior of the carrier and being adapted for use as a handle to permit actuation of said slidable connection, and latching means to hold the slide and closure against movement relative to the carrier adapted to be released by a movement of said closure in a direction at an angle to that in which said connection slides.

5. In combination with a pneumatic despatch tube carrier, a slidable connection to one side of the interior of said carrier and extending longitudinally of the latter, load ejecting means, to engage the inner end of a roll of paper or the like, which may constitute the load to be despatched in said carrier, and operable by said slidable connection, a closure for said carrier at the outer end of said connection and operable together therewith, said closure when open being movable to a position to permit egress of the load from said carrier and constituting a handle to permit actuation of said slidable connection, and latching means, a part of which is disposed at the aforesaid side of said carrier, to co-act with a second part of said latching means carried by said connection, to restrain the latter against movement, said parts being separable by a movement of said closure in a direction substantially at right angles to that in which said connection slides.

6. A carrier for despatch systems comprising a receptacle having a hinged closure free to move laterally when closed and latch parts for said closure to retain it in its receptacle closing position, said latch parts being on the side of said closure adjacent the hinge thereof and releasable on moving the closure laterally.

7. A carrier for despatch systems comprising a receptacle having a closure attached thereto adjacent to one side of said receptacle, latch parts for said closure to retain it in its receptacle closing position, said latch parts being on the aforesaid side of said receptacle, means to permit said closure to be moved bodily outward from said receptacle when said latch parts are disengaged, and provisions to permit said closure to be moved laterally with respect to the line of movement in which it travels when being moved bodily as aforesaid, to disengage said latch parts.

8. A carrier for despatch systems comprising a receptacle having a closure attached thereto, latch parts for said closure to retain it in its receptacle closing position, means to permit said closure to be moved bodily outward from said receptacle when said latch parts are disengaged, and provisions causing said closure to be moved at an angle to the line of movement in which it travels when being moved bodily as aforesaid.

In testimony whereof I have affixed my signature, in the presence of two witnesses.

FRED R. TAISEY.
